CLAIM

The ornamental design for a lid for ashtray, as shown and described.

DESCRIPTION

FIG. 1 is a front, right and bottom perspective view of a first embodiment of a lid for ashtray, showing my new design; FIG. 2 is a rear, left and top perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof.

FIG. 9 is a sectional view of portion of FIG. 3 thereof.

FIG. 10 is a front, right and bottom perspective view of a second embodiment of the lid for ashtray;

FIG. 11 is a rear, left and top perspective view thereof;

FIG. 12 is a front view thereof;

FIG. 13 is a rear view thereof;

FIG. 14 is a left side view thereof;

FIG. 15 is a right side view thereof;

FIG. 16 is a top plan view thereof;

FIG. 17 is a bottom plan view thereof; and

FIG. 18 is a sectional view of portion of FIG. 12 thereof.

FIG. 19 is a front, right and bottom perspective view of a third embodiment of the lid for ashtray;

FIG. 20 is a rear, left and top perspective view thereof;

FIG. 21 is a front view thereof;

FIG. 22 is a rear view thereof;

FIG. 23 is a left side view thereof;

FIG. 24 is a right side view thereof;

FIG. 25 is a top plan view thereof;

FIG. 26 is a bottom plan view thereof; and

FIG. 27 is a sectional view of portion of FIG. 21 thereof.
